(57) **CLAIM**

I claim the ornamental design for artificial fishing lure, as shown and described.

DESCRIPTION

FIG. 1 is an perspective top, rear and left side view of the artificial fishing lure showing my design.

FIG. 2 is an orthographic right side view of my artificial fishing lure showing my design.

FIG. 3 is a top plan view thereof;

FIG. 4 is a bottom plan view thereof;

FIG. 5 is an perspective bottom, rear and right side view of the artificial fishing lure showing my design; and,

FIG. 6 is a rear view.

The broken line showing of environment in the drawings is included for the purpose of illustrating only and forms no part of the claimed design.
